SCAFFOLD JACK

Carl M. Jahn, 2640 St. Paul St., Denver, Colo.
Filed Feb. 8, 1960, Ser. No. 7,476
6 Claims. (Cl. 248—240)

This invention relates to facilities useful in various orders and stages of building construction and related operations to transiently support scaffolding, platforms, and the like, from and exteriorly of vertical wall structures, and more particularly to such facilities adapted for expeditious functional coaction with features conventionally characterizing outer face areas of concrete wall forms, and has as an object to provide a novel and improved scaffold jack of uniquely advantageous utility.

A further object of the invention is to provide a novel and improved scaffold jack that is simple and convenient of detachable use association with and removal from conventionally-featured concrete wall forms by a single operator without recourse to other equipment or special tools.

A further object of the invention is to provide a novel and improved scaffold jack that is compact in a unitary organization conditioned for immediate practical use.

A further object of the invention is to provide a novel and improved scaffold jack that is dependably secure in self-sustaining coaction with characteristic features of conventional concrete wall forms.

A further object of the invention is to provide a novel and improved scaffold jack that is susceptible of expedient, economical production in any appropriate size range from readily-available materials.

A further object of the invention is to provide a novel and improved scaffold jack that is rugged and durable throughout a long life of repetitious use.

A further object of the invention is to provide a novel and improved construction and operative organization of elements constituting a scaffold jack especially adapted for advantageous use association with conventionally-featured concrete wall forms.

With the foregoing and other objects in view, my invention consists in the construction, arrangement, and operative combination of elements as hereinafter set forth, pointed out in my claims, and illustrated by the accompanying drawing, in which—

FIGURE 1 is a fragmentary, somewhat-diagrammatic, perspective view of a conventionally-featured concrete wall form exterior areas in supporting coaction with a typical embodiment of the invention.

FIGURE 2 is a vertical, end elevational view, on a relatively-enlarged scale, of the jack unit according to FIGURE 1 as positioned in and separated from the mounted association thereof distinguishing the preceding view.

FIGURE 3 is a top plan view of the jack unit as represented by FIGURE 2, an alternative limiting position of relatively-movable components thereof being indicated by broken lines.

FIGURE 4 is a side elevational view of the jack unit according to the preceding views with the movable components thereof disposed as represented by the broken line showings of FIGURE 3.

As fragmentarily typified by FIGURE 1, it is common practice to organize concrete wall forms from suitable, vertically-disposed, flat panel members 10 spacedly interrelated by means of conventional tie-rods having headed terminal portions 11 arranged to project exteriorly of the panel traversed by the rod for coaction with a clamp bracket 12 adapted to receive and support a brace timber 13 thereby tightly pressed against the associated panel in reaction to adjustment of a wedge plate 14 effective between and to separate opposed areas of each said bracket 12 and the head of the rod terminal portion 11 coacting

2

therewith. In some diversity of structural particularity, the clamp brackets 12 extensively in use are of open loop form presenting a through opening parallel to and beneath the timber 13 operatively associated therewith, to and from which opening transit in a direction perpendicular to the panel is inhibited, and it is customary in the erection of forms comprised from the panel, tie-rod, clamp bracket, and timber elements just discussed to arrange the tie-rods with their associated brackets in uniformly-spaced alignment both vertically and horizontally of the form wall, whereby to establish a vertical, uniformly-spaced series of horizontally-disposed brace timbers 13 exteriorly of the completed form structure. Incident to the erection, and to the ultimate impletion, of the forms constituted as herein set forth there is frequent occasion for workmen to function at elevations along the form beyond normal reach from the ground, or other form base, with consequent necessity for scaffolding supplemental to the form wall, or walls, and the instant invention is hence directed to the provision of a novel, improved, fully practical, and advantageous scaffold jack expedient of operative association with conventional concrete forms characterized by clamp brackets of laterally-open loop type in supporting relation with horizontal brace timbers.

In any appropriate size and strength of its rigid components, and in a range of component dimensions and proportions operatively coactable with the dimensional characteristics of conventional spacings and arrangements of the form wall features, the improved jack of the invention is a unitary assembly of foldably-related elements cooperably integrated with a straight, rigid, expediently-tubular member 15 of a diametric size freely and loosely receivable in and through the lateral openings of the conventional clamp brackets 12 and of a length to span between, engage within, and desirably extend at each end slightly beyond the clamp brackets 12 of an adjacently-spaced pair thereof supporting a horizontal beam 13 in a given conventional form wall arrangement. Securely affixed to and inwardly adjacent the ends of the member 15, rigid arms 16 of material similar to or the same as that of said member are spaced apart along the latter a distance less than the spacing between adjacent clamp brackets 12 such as will permit shift of the member 15 axially to release of one or the other of its ends from engagement therewith, and said arms 16 extend, preferably with moderate convergence, outwardly from the same side of said member in a common plane radial of the latter an equal distance to terminate in opposed, inturned ends rotatably supporting a sleeve 17 in axial parallelism with the member 15. In a length feasibly approximating that of the member 15, the arms 16 are adapted to outstand perpendicularly from a form wall having clamp brackets 12 traversed by ends of the member 15, as indicated in FIGURE 1, and thereby provide a horizontal platform for the support of planks, decking, and the like, whereon workmen may operate, in which disposition said arms are disposed and maintained by a strut 18 of suitable rigid, expediently-tubular material affixed centrally to and radially of the sleeve 17 in a length terminated by a transverse, angular shoe 19 such as to incline inwardly of the form wall to engagement of said shoe with the beam 13 second below that adjacent the member 15 when the plane of the arms 16 is substantially horizontal. Operable as a loaded bearing member, the shoe 19 is provided in substantial length and symmetrical attachment to the strut 18 to conformably overlie an upper, outer corner of the beam thereby engaged and, in the interest of safety and security, said shoe is formed with a hole 20 through the web thereof vertical in position of jack use for the accommodation of a nail in seated relation with the beam therethrough for consequent detachable connection of the shoe to the beam in a manner

inhibiting their accidental separation. Distribution and minimizing of the load applied to the clamp brackets through the member 15 therewith engaged is the function of a second angular shoe 21 affixed along one of its flange margins to and generally tangentially of the member 15 between the arms 16 to dispose its free flange spacedly parallel to the plane of said arms and directed across the said member away from the arms, whereby to present the said free flange of the shoe 21 for overlap on and bearing engagement with the upper outer corner of the beam 13 immediately superjacent the member 15 as associated in position of use therewith. The free flange of the shoe 21 parallel to the plane of the arms 16 is spaced from and radially of the member 15 a distance appropriate to accommodate the thickness of conventionally-sized beams 13 and the spacing of the member 15 therefrom incident to coaction of the latter with the clamp brackets 12, and the fixed flange of said shoe is offset moderately and toward the sleeve 17 from the peripheral zone of the member 15 whereto it is marginally attached in order to effect intended secure interengagement of said shoe and beam as said member is rotated in mounted association with the clamp brackets to elevate the sleeve 17 for operative positioning of the strut 18, as shown and described. The operatively-complete jack unit thus far described is advantageously supplemented by a tubular socket 22 fixed to and radially of the sleeve 17 in an angular relation such as to extend said socket above and substantially perpendicular to the plane of the arms 16 when the member 15 and strut 18 are engaged with the appropriate form wall components for attachment of the jack unit in position of use thereto, in which relationship and disposition the socket 22 functions as a stop to limit lateral displacement of loose planks, decking, and the like, outwardly of the form wall away from support on and by the jack unit arms 16 and is simultaneously available for convenient attachment to the mounted jack unit of uprights thereby disposed to serve as, or to mount, safeguards for those utilizing the scaffold.

Practical use and operation of the improvement should be reasonably manifest. In appropriate size and lightweight construction foldable to compact form about the axis of the sleeve 17, as in FIGURE 4, the jack is a unit manipulable by a single operator to use position on, or detachment from, a form wall of appropriate conventional organization. Upon occasion for an elevated scaffold along a form wall characterized by vertically-spaced, horizontal beams seated in horizontally-spaced, laterally-open clamp brackets, the jack unit of the invention size-proportioned to the conventional beam and bracket spacing of the form wall is a practical reusable facility conservative of materials and labor. Alike in a length of member 15 suited to span between and end-engage through horizontally-paired, adjacent clamp brackets of the form wall and a length of strut 18 appropriately correlated with the vertical spacing separating the form wall beams, a plurality of the jack units is mounted on and in spaced, horizontal succession along the wall with the arms 16 thereof horizontally coplanar in outward projection from the wall for the reception and support of scaffold floor elements. Each of the jack units is assembled to the form wall by first entering one end of the member laterally through a selected bracket 12 while the unit arms 16 are inclined outwardly and downwardly of the wall, shifting the entered member 15 axially through the bracket engaged thereby until the other end of the member clears the complementary bracket of the pair, reversely shifting said member to engagement at its free end through said complementary bracket, upwardly rocking the arms 16 on the axis of the so-engaged member to embracing coaction of the shoe 21 with the upper outer corner of the beam superjacent the member 15 and to a position accommodating seating of the strut shoe 19 on the upper outer corner of a subjacent beam, and finally securing said shoe 19 to its beam with a nail entered

through the hole 20 of the shoe. Secure and stable in the wall-mounted disposition shown and described, the jack unit functions in a horizontal, spaced succession of like facilities to position and support scaffold floor members applied thereto, loosely or in any feasible fixed relation, for the accommodation of workmen, materials, and equipment, hand grips, steady poles, and protective rails being supplied in detachable coaction with the vertically and upwardly directed sockets 22 of the several jack units as may be deemed to be requisite or desirable. Disassembly of the erected scaffold and recovery of the several jack units in condition for immediate reuse is an obvious reversal of the procedures above outlined susceptible of effectuation by a single workman without recourse to specialized equipment or tools.

Since changes, variations, and modifications, in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A scaffold jack particularly adapted for operative association with vertical walls of concrete forms secured in use position by means including; spacedly-correlated, laterally-open brackets stationarily protruding outwardly from the form wall and beams supported in edge engagement with the wall on and spanning between the brackets in each horizontal succession thereof, said jack comprising a rigid, planar frame formed with spacedly-parallel side members, coaligned end portions of one of said members oppositely extended beyond the frame receivable in corresponding journaled engagement through the lateral openings of contiguous, horizontally-paired brackets subjacent and parallel to the beam supported thereby, whereby to hingedly link said frame to the wall for actuation through a vertical arc plane-perpendicular to the wall, an angular shoe affixed intermediately of and to parallel said one member as a clip actuatable with and opening away from the frame adapted to conformably engage over an opposed salient corner of the adjacent beam as an incident of and to upwardly limit frame actuation in its journaled mounting, and means radial of and connected for angular adjustment relative to the other of said parallel side members selectively coactable with other beam components of the wall to retain said frame at the upward limit of its actuatable range established by inter-engagement of said shoe and beam.

2. A scaffold jack particularly adapted for operative association with vertical walls of concrete forms secured in use position by means including; spacedly-correlated, laterally-open brackets stationarily protruding outwardly from the form wall and beams supported in edge engagement with the wall on and spanning between the brackets in each horizontal succession thereof, said jack comprising a rigid, planar frame formed with spacedly-parallel side members, coaligned end portions of one of said members oppositely extended beyond the frame receivable in corresponding journaled engagement through the lateral openings of contiguous horizontally-paired brackets subjacent and parallel to the beam supported thereby, whereby to hingedly link said frame to the wall for actuation through a vertical arc plane-perpendicular to the wall, an angular shoe affixed intermediately of and to parallel said one member as a clip actuatable with and opening away from the frame adapted to conformably engage over an opposed salient corner of the adjacent beam as an incident of and to upwardly limit frame actuation in its journaled mounting, a rigid strut radial of and connected for angular adjustment relative to the other of said parallel side members, and a shoe diametrically terminating said strut for selective coaction with salient corners of other beam components of the wall at the upward limit of the range of frame actuation

established by interengagement of said first shoe and beam.

3. A scaffold jack particularly adapted for operative association with vertical walls of concrete forms secured in use position by means including; spacedly-correlated, laterally-open brackets stationarily protruding outwardly from the form wall and beams supported in edge engagement with the wall on and spanning between the brackets in each horizontal succession thereof, said jack comprising a rigid, planar frame formed with spacedly-parallel side members, coaligned end portions of one of said members oppositely extended beyond the frame receivable in corresponding journaled engagement through the lateral openings of contiguous, horizontally paired brackets subjacent and parallel to the beam supported thereby, whereby to hingedly link said frame to the wall for actuation through a vertical arc plane-perpendicular to the wall, an angular shoe affixed intermediately of and to parallel said one member as a clip actuatable with and opening away from the frame adapted to conformably engage over an opposed salient corner of the adjacent beam as an incident of and to upwardly limit frame actuation in its journaled mounting, an elongated sleeve rotatably embracing the other of said parallel side members, a rigid strut fixed radially of said sleeve, and a shoe diametrically terminating said strut parallel to said first shoe for selective coaction with salient corners of other beam components of the wall at the upward limit of the range of frame actuation established by interengagement of said first shoe and beam.

4. The organization according to claim 3, wherein a socket opening radially of the sleeve is affixed thereto in an angular relation with the strut such as to upstand from and substantially perpendicular to the plane of the mounted frame when the latter is held by the strut at the upward limit of its range of actuation.

5. A scaffold jack particularly adapted for operative association with vertical walls of concrete forms secured in use position by means including spacedly-correlated, laterally-open brackets stationarily protruding outwardly from the form wall and beams supported in edge engagement with the wall on and spanning between the brackets in each horizontal succession thereof, said jack comprising a straight, rigid member rotably receivable through

lateral openings of said brackets in a length exceeding the horizontal spacing separating adjacent brackets of a pair thereof, complementary arms end-fixed in spaced relation to and inwardly from the ends of said member defining a plane radial thereof, an elongated sleeve rotatably conjoining ends of said arms remote from said member in spaced parallelism with the latter, a rigid strut fixed radially of said sleeve, an angular shoe diametrically terminating said strut parallel to said member disposed for bearing coaction with a beam corner, and a second angular shoe marginally affixed to said member between said arms as a clip opening away from said arms above the plane common thereto.

6. A scaffold jack particularly adapted for operative association with vertical walls of concrete forms secured in use position by means including; spacedly-correlated, laterally-open brackets stationarily protruding outwardly from the form wall and beams supported in edge engagement with the wall on and spanning between the brackets in each horizontal succession thereof, said jack comprising a straight, rigid member rotably receivable through lateral openings of said brackets in a length exceeding the horizontal spacing separating adjacent brackets of a pair thereof, complementary arms end-fixed in spaced relation to and inwardly from the ends of said member defining a plane radial thereof, an elongated sleeve rotatably conjoining ends of said arms remote from said member in spaced parallelism with the latter, a rigid strut fixed radially of said sleeve, a socket fixed radially of said sleeve in obtusely-angular opposition to said strut, an angular shoe diametrically terminating said strut parallel to said member disposed for bearing coaction with a beam corner, a passage for accommodation of a fastener intersecting said shoe, and a second angular shoe marginally affixed to said member between said arms as a clip opening away from said arms above the plane common thereto.
